United States Patent Office

Des. 198,592
Patented July 7, 1964

198,592

JUG

Richard L. Platte, Ann Arbor, Mich., assignor to Hoover
Ball and Bearing Company, Salin, Mich.

Filed Feb. 17, 1964, Ser. No. 78,648

Term of patent 14 years

(CL D58—5)

—FIG. 1

—FIG. 4

FIGURE 1 is a side elevational view of a jug, showing my new design;

FIGURE 2 is an end elevational view thereof as seen from the right of FIGURE 1;

FIGURE 3 is an end elevational view thereof as seen from the left of FIGURE 1; and

FIGURE 4 is a top plan view thereof.

The dominant features of my design reside in the portions shown in full lines.

I claim:

The ornamental design of a jug, substantially as shown and described.
